(57) **CLAIM**

The ornamental design for a footwear with grid pattern, as shown and described.

DESCRIPTION

FIG. 1 is a right side elevational view of footwear with grid pattern, showing my new design.

FIG. 2 is a left side elevational view thereof.

FIG. 3 is a rear elevational view thereof; and,

FIG. 4 is a left side elevational view thereof, shown in an alternate environment.

The broken lines portions of FIGS. 1–4 are included to show unclaimed subject matter in use only and form no part of the claimed design.

1 Claim, 4 Drawing Sheets
